CHARLES B. BRISTOL, OF NEW HAVEN, CONNECTICUT.

Letters Patent No. 87,240, dated February 23, 1869.

IMPROVED COMPOSITION MARTINGALE-RING.

The Schedule referred to in these Letters Patent and making part of the same.

To all whom it may concern:

Be it known that I, CHARLES B. BRISTOL, of New Haven, in the county of New Haven, and State of Connecticut, have invented a new Improvement in Martingale-Rings; and I do hereby declare the following, when taken in connection with the accompanying drawings, and the letters of reference marked thereon, to be a full, clear, and exact description of the same, and which said drawings constitute part of this specification, and represent, in—

Figure 1, a view of the ring complete;

Figure 2, a section of the ring split in halves; and in Figure 3, a transverse section.

Martingale-rings, as heretofore constructed, have been formed from bone, ivory, rubber, or from solid metal covered by a composition. If formed from bone, rubber, or ivory, the rings are easily broken, and if from solid metal, covered or uncovered, the rings are too heavy.

The object of my invention is to produce a covered ring which shall have the appearance of other material than metal, and yet be sufficiently light to be unobjectionable. To this end,

My invention consists in constructing a hollow ring sufficiently thick only to sustain itself, then coating the ring with rubber or similar material, and completing the whole by a curing-process, according to the nature of the material. I prefer the material known as hard-rubber compound.

In order to the clear understanding of my improvement, I will fully describe the same, as illustrated in the accompanying drawings.

I first form a ring, B, from a tube or otherwise, so that the ring be hollow; (the metal may be very thin, as the strain upon the ring is very slight;) then coat the ring with any suitable material, as seen in figs. 2 and 3, preferring hard rubber, and finish the whole by a curing-process, adapted to the nature of the material with which the ring is covered.

I am aware that metallic rings have been covered with composition, but such rings have been made solid, and to these the same objections exist as to all metal rings, whereas, in my invention, the ring is very little if any heavier than the common bone or ivory ring, and is much stronger than either, and has the appearance of either one or the other, according to the color of the coating.

Having thus fully described my invention,

What I claim as new and useful, and desire to secure by Letters Patent, is—

As an article of manufacture, the herein-described martingale-ring, consisting of the hollow ring B, covered and finished substantially as set forth.

CHAS. B. BRISTOL.
